UNITED STATES PATENT OFFICE.

WILLIAM GASTON, OF NEW YORK, N. Y.

GOLF-GAME APPARATUS.

Application filed July 26, 1926. Serial No. 125,041.

My invention relates to a game employing a board of the general character of a checker board, and particularly relates to a checker board modified to embody features 5 characteristic of the actual playing of golf, which board is further characterized by the fact that certain squares of the checker board are trapped with bunkers, sand-pits, water hazards, rough and out-of-bounds to 10 simulate a golf course.

The general object of my invention, therefore, is to provide a board of the character of a checker board embodying the golf features referred to in a practical manner, to 15 provide a game having interest beyond that of the game of checkers, while embodying certain characteristics of the game of checkers.

Reference is to be had to the accompanying drawings, forming part of this specification, it being understood that the drawings are merely illustrative of one example of the invention.

Figure 1 is a plan view of a game board 25 embodying the invention;

Figure 2 is an edge view of the game board.

Figures 3 and 4 are perspective views showing examples of pieces to be employed 30 in playing the game.

The board 10 shown in Figure 1 is arranged in general like a checker board, but modified. Said board has three rows of alternate squares 11 and 12, being differentiated by coloring or otherwise. Said squares are adapted to receive a total of twenty-seven pieces such as the pieces 13 shown in 35 Figure 3, simulating one-half of a golf ball. The two series of three rows each of squares 11 and 12 are separated by a field for playing, there being illustrated in the latter, for example four rows of squares, alternate squares 14 and 15 being differentiated by coloring or otherwise. The numeral 40 112 indicates disc-like figures in the spaces 12 to receive the pieces 13, 113.

Interposed in some of the rows of squares in the playing field are bunkers 16 and roughs 17; also in certain squares in the field representations of trees or the equivalent indicate "out of bounds" as indicated 45 at 18. Disposed on the field, made up of the rows of squares, between the series of

squares 11 and 12 are lakes 19, made in the form of a chain of lakes connected by the 55 representation of streams 20.

The squares 14 represent the fairway. In addition to said rows of squares 11, 12, 14 and 15, additional rows of squares are provided along each edge of the board and beyond the rows of squares 11 and 12, said additional squares being known as the "birdie-head" of the course, and being indicated by the numeral 21 and separated by 60 distinguishing squares 22. Adjacent certain of the green squares 21 in the birdie-head are sand traps 23. The numeral 113 indicates one of the feathered or birdie pieces, which enters the play in lieu of a piece 13, whenever the piece 13 reaches, in 70 the play, the birdie head having the series of birdie squares 21.

Definitions.

A "side" consists either of two players or 75 four players. If one player play against another the match is termed a "twosome." If two play against two, each side playing one set of balls or pieces, the match is called a "foursome."

The "course" is the whole area within 80 which play is permitted, or that area between the two separated series of squares 11 and 12. Specifically, the course is composed of the dark green or fairway squares 85 12, that is, two rows of nine squares for each player, or eighteen in all.

A "hazard" is any bunker, sand-trap, pond or lake, or a rough.

"Out of bounds" is all the ground in 90 which play is supposed to be prohibited. The ball is out of bounds when played out of the prohibited area, as for example, on to the square 18.

"En prise": A ball is said to be en prise 95 when it is under attack.

"Forevantage": This term describes an opening in which the ball is voluntarily sacrificed at an early stage of the game, in order subsequently to gain an advantage.

"Fore!" is the expression generally used when a player touches a piece 113, either a ball or a birdie, with the intention of making a move.

"Stymied" describes that state of the 105 game when one of the players is so placed

or maneuvered that he cannot move without losing a ball or piece.

“Foolzle”: A player is said to “foozle” when he omits to take a ball or birdie en prise; the non-taking ball being forfeited and removed from the course by way of penalty.

The method of moving the pieces and playing the game.

10 Each player is required to play with a different colored set of pieces, that is, red or white pieces. The players exchange pieces after each game. Lots are cast for the 15 choice of color at the commencement of a match.

The aim pursued is to capture or trap the balls or pieces of the adversary, or to so hem them in that they cannot be played. When 20 either player is reduced to such a condition that he has no pieces left with which to play, the game is at an end.

The pieces are moved one square at a time 25 diagonally to right or left and to any adjacent square which for the time being is vacant. The pieces or balls can only move in a forward direction, until they reach the furthest row at the adversary's side of the board, known as the “birdie head” of 30 the course, at which time they become known as “birdies”. From thence forward the pieces can be moved backward or forward at the pleasure of the player but the pieces are still limited to one square or green at 35 each move.

When a ball becomes a “birdie” the fact is denoted by the piece being feathered, that is to say, removed from the green and a birdie or feathered piece substituted in its place.

40 When two opposing pieces or balls come into juxtaposition with a vacant space behind either of them, the piece is said to be “en prise” and becomes liable, when it is the adversary's turn to play, to be taken out.

45 The ball which is taken is removed from the course and the capturing ball remains on. If, after making one move or jump, another ball stands in position to be jumped, it is jumped on the same turn or move, but when 50 a birdie green is reached, whether by a jump or otherwise, that play ends the move until the other player has moved, except when a ball already a birdie jumps in. It may then jump out again if a ball stands in the way of 55 being captured.

When a ball is played into a bunker, sand trap, rough, or out-of-bounds, a loss of one ball “penalty” is incurred by the player. It is then optional with said player to remove

from the course any remaining ball of his own other than the one trapped.

Balls played into a lake or pond are lost balls and must be removed from the board at once. Also under these circumstances an additional ball or piece is forfeited by way of penalty.

Playing forward or backward over trapped greens involves the loss of one ball as a penalty. After a player foozles, the opposing player has the power either to compel 70 the take, or to let the ball remain on the course, as he thinks proper.

If a ball or birdie, in making a capture, reaches a bunker, sand-trap, rough, or out-of-bounds, and is brought into juxtaposition with another ball or birdie of the opponent, the player cannot as part of the same move continue to capture after entering a trap.

A capture in play as well as an ordinary play is considered completed as soon as the 80 hand is withdrawn from the ball or piece played.

I would state furthermore that while the illustrated example constitutes a practical embodiment of my invention, I do not limit 85 myself strictly to the exact details herein illustrated, since, manifestly, the same can be considerably varied without departure from the spirit of the invention, as defined in the appended claims.

90 What I claim is:

1. In a game device, a board having delineated thereon the following, to wit: two series of rows of spaces to accommodate pieces for the playing of the game, and a 95 playing field between said rows of spaces, and divided into corresponding spaces alining obliquely with the first mentioned spaces, certain spaces in said playing field having hazards indicated adjacent thereto, 100 said hazards including sand traps, bunkers, ponds and out of bounds.

2. In a game device, a board having delineated thereon three rows of spaces, nine spaces in each row, separated by intervening 105 spaces distinguished from the first spaces, the spaces in the respective rows alining obliquely, a playing field between said two series of spaces of three rows each, and divided into separate spaces alining obliquely 110 with the spaces in said two series of rows, and a row of spaces along each of the said series of rows on that side remote from said playing field, the said playing field and the last mentioned rows of spaces remote from 115 the playing field having hazards adjacent thereto.

WILLIAM GASTON.
